FLEXIBLE ATTACHMENT FOR SMOKING PIPES

Sam Kanter, Chicago, Ill.

Application January 7, 1932, Serial No. 585,361
Renewed January 19, 1934

3 Claims. (Cl. 131—12)

My invention relates to improvements in flexible attachment for smoking pipes, and it consists in the combinations, constructions, and arrangements herein described and claimed.

5 An object of my invention is to provide a flexible attachment for smoking pipes which when used will enable the smoker to knock ashes from the bowl of his pipe without breaking the joint or connection between the pipe bowl and the pipe stem.

10 A further object of my invention is to provide a flexible attachment whereby a pipe may be safely kept even in the hip pocket without danger of breaking the pipe or pipe stem.

15 A further object of my invention is to provide means whereby the viscous tobacco fluid may be deposited on certain metal parts of the pipe which may be easily removed from the pipe and thereafter cleaned.

20 A further object of my invention is to provide a pipe which is novel in construction, durable and convenient in use, and efficient for the purposes intended.

25 Other objects and advantages will appear in the following specification, and the novel features of the invention will be particularly pointed out in the appended claims.

30 My invention is illustrated in the accompanying drawing, forming part of this application, in which

Figure 1 is an elevational view of a smoking pipe having the device of my invention applied thereto,

35 Figure 2 is a fragmentary sectional view of the pipe shown in Figure 1,

Figure 3 is a section taken along the line 3—3 of Figure 2, and

Figure 4 is a sectional view of a modified form of my invention.

40 The attachment device of my invention is designed for use with a smoking pipe having a bowl 1 and a stem 2. In carrying out the preferred form of my invention, I make use of a flexible casing 3 which may be made of any suitable material, such as, for instance, rubber or fabric, and a wooden, metal or composition tube 4.

45 I may also make use of a small metal tube 5 to which may be secured a helical metal element 6. If desired, the helical element 6 may be welded, soldered or otherwise connected to the metal tube 5. The attachment may be assembled substantially as shown in the accompanying drawing. The flexible casing 3 may be of any convenient length. The helical element 6 in combination with the small tubular element 5 provides means

whereby the tubular casing 3 may be prevented from flexing too easily. The elements 5 and 6 also provide means whereby the viscous tobacco fluid may be removed from the interior of the casing 3.

50 In operation, the device of my invention may be disconnected from the pipe bowl 1 and the stem 2. The tubular element 5 and the helical element 6 may be removed from the casing by pressing the inner end of the element 5 against the tubular element 4 until the outer end of the helical element extends beyond the outer end of the tubular casing 3. The helical element may then be grasped by the fingers and the tubular element withdrawn from the casing.

55 If desired, the tubular element 4 may be withdrawn from the inner end of the flexible casing 3. The tubular element 5 and the helical element 6 may then be readily removed from the flexible casing 3 by grasping the tubular element 5. It will of course be understood that if desired the tubular element 5 may be omitted.

60 In this case the helical element 6 may either be rigidly connected to the tube 4 or it may be entirely disconnected.

65 From the foregoing description of the various parts of the device, it is apparent that the attachment device of my invention provides means whereby the pipe stem and the bowl may be moved angularly with respect to each other. The elements 5 and 6 besides adding to the rigidity of the flexible casing also provide means whereby the small bore of the pipe stem and pipe bowl may be readily cleansed.

70 In Figure 4 I have shown a modified form of the flexible casing in which a flexible tubing 3' is reinforced by a helical spring 7.

75 It will of course be understood that, if desired, the device of my invention may be rigidly connected to either the bowl 1 or the stem 2.

I claim:

1. An attachment of the character described adapted for connection between the mouthpiece and bowl of the pipe, said attachment including a flexible tubular casing, a tubular connection 100 means projecting from one end of said casing, and a pipe cleaning means, said pipe cleaning means comprising a helical spring member and a tubular metal member, said helical spring member being fixedly secured to said tubular metal member, 105 said pipe cleaning means being removably disposed within said tubular casing.

2. A smoking pipe comprising a bowl, a stem, a flexible tubular member connecting said bowl and stem and forming a smoke passage between 110

said bowl and stem, said member permitting angular movement of said stem with reference to said bowl, and a flexible helical spring within said member to support the walls thereof to prevent undue flexing thereof under the weight of said bowl.

3. A smoking pipe comprising a bowl having a smoke passage, a separate stem having a smoke passage, a separate flexible tubular member connecting said bowl and stem and through which

smoke passes from one of said passages to the other, a flexible helical spring within said flexible member for supporting the walls thereof and a tube secured to one end of said spring and extending beyond the end of said flexible member into one of said passages to provide means for conveniently withdrawing said spring from said tubular member for cleaning the latter.
